COMBINATION PEDESTAL SPEAKER AND LAMP

Arthur Robson, Jericho, N.Y., assignor to Morse Electro Products Corp., Brooklyn, N.Y.

Filed Aug. 21, 1972, Ser. No. 282,448

Term of patent 14 years

Int. Cl. D26—05; D14—01

U.S. Cl. D48—20 D

FIG. 1 is a top plan view of the combination pedestal speaker and lamp showing my new design;

FIG. 2 is a front elevation view thereof, the rear elevation view being substantially identical;

FIG. 3 is a bottom plan view thereof; and

FIG. 4 is an enlarged portion of the faceted surface shown in FIG. 2, which is to be understood to be continuous over the upper half of the sphere portion of the combination pedestal speaker and lamp.

The faceting on the upper half of the sphere is omitted for convenience of illustration and the cross-hatching on the lower half of the sphere is partially shown for convenience of illustration. It is understood, however, that the faceting and the cross-hatching are uniformly continuous over the upper and lower halves of the sphere, respectively.

I claim:

The ornamental design for a combination pedestal speaker and lamp, as shown and described.
